United States Patent Office

Des. 233,706

Patented Nov. 19, 1974

233,706

STAND FOR REAL ESTATE SIGN

Thomas A. Battaglia, 43 Manor Road,
Kentfield, Calif. 94904

Filed Oct. 9, 1973, Ser. No. 404,167

Term of patent 14 years

Int. Cl. D20—03

U.S. Cl. D96—12 A

FIG. 1

FIG. 2.

FIG. 1 is a front elevation view of a stand for a real estate sign; and

FIG. 2 is a side elevation of the stand.

I claim:

The ornamental design for a stand for real estate sign, as shown and described.
